(57) **CLAIM**

The ornamental design for a data processing machine, as shown and described.

DESCRIPTION

This article is a data processing machine used as a facsimile, a copier, a scanner, or a printer or a multifunctional machine of any combination thereof.

FIG. 1 is a perspective view of our design for a data processing machine of the present invention;

FIG. 2 is a front view thereof;

FIG. 3 is a rear view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a perspective view of our design for a data processing machine according to a second embodiment of the present invention;

FIG. 9 is a front view thereof;

FIG. 10 is a rear view thereof;

FIG. 11 is a top plan view thereof;

FIG. 12 is a bottom plan view thereof;

FIG. 13 is a right side elevational view thereof; and,

FIG. 14 is a left side elevational view thereof.
